(57) **CLAIM**

The ornamental design for a plush elephant, as shown and described.

DESCRIPTION

FIG. 1 is a front elevation view of a plush elephant showing our new design;

FIG. 2 is a left side elevation view thereof;

FIG. 3 is a rear elevation view thereof;

FIG. 4 is a top plan view thereof;

FIG. 5 is a bottom plan view thereof; and,

FIG. 6 is a right side elevation view thereof.

The broken lines shown in the drawing are for illustrative purposes only and form no part of the claimed design.

The nose of the elephant shown in the drawing is lined for the color red.
